BICYCLE OR SIMILAR ARTICLE

Henry Worthington Kalt, Valley Stream, N. Y., assignor to Kalt, Breeding & Hadden, Inc., a corporation of New York

Application June 14, 1954, Serial No. 30,988

Term of patent 7 years

(Cl. D90—8)

Fig. 1 is a perspective view of a bicycle or similar article showing my new design. The side opposite to that shown in Fig. 1 has substantially the same appearance as the side shown in such Fig. 1.

Fig. 2 is a rear view of the full line portion of Fig. 1. The dominant features of my new design are shown in full lines in the drawings.

I claim:

The ornamental design for a bicycle or similar article, as shown and described.
